W. R. DUNCAN

ELECTRIC STOP FOR PHONOGRAPHS

Filed Feb. 1, 1923

Witness:

W. K. Olson

By Glenn S. Noble Attel

Inventor:
WILLIAM R DUNCAN

UNITED STATES PATENT OFFICE.

WILLIAM R. DUNCAN, OF CHICAGO, ILLINOIS.

ELECTRIC STOP FOR PHONOGRAHS.

Application filed February 1, 1923. Serial No. 616,335.

To all whom it may concern:

Be it known that I, WILLIAM R. DUNCAN, a citizen of the United States, residing at Chicago, in the county of Cook and State 5 of Illinois, have invented certain new and useful Improvements in Electric Stops for Phonographs, of which the following is a specification.

This invention relates to automatic electrically operated stopping mechanism for phonographs or talking machines and while certain features thereof may be adapted for general application, it is particularly intended for use in connection with the Edison 10 phonograph. In this type of phonograph there is a floating weight which forms a part of the reproducer and when the stylus reaches the end of the groove in the record the free end of the weight is raised and 15 moves laterally to one side or has a swinging movement on its vertical axis. This movement is comparatively slight and cannot always be depended upon in the normal operation of the device, for actuating an 20 ordinary switch or stop releasing mechanism.

The principal object of this invention is to provide an electric stop for Edison phonographs which may be relied upon and which 25 will be efficient in operation. Other objects are to provide auxiliary means for ensuring the closing of an electric switch by the lateral movement of the floating weight; to provide an electric stop mechanism of this 30 character which may be attached without insulating the floating weight; to provide means for multiplying the movement of the floating weight whereby an electric switch may be satisfactorily operated; and in general 35 to provide such improved features and advantages as will appear more fully from the following description.

In the accompanying drawings illustrating this invention:

40 Figure 1 is a plan view of a phonograph with parts broken away to show the stop mechanism;

Figure 2 is a side view with parts broken away to show the interior construction;

50 Figure 3 is an enlarged detail showing my improved switch mechanism as applied to the reproducer; and

Figure 4 is a sectional view taken on the line 4—4 of Figure 3.

55 In the particular form of invention as shown in these drawings, a phonograph 5

is provided with a motor plate 6 and a turntable 7 for supporting the record 8. It is also, of course, provided with the necessary motor and other parts but as these form no part of the present invention they are not illustrated. The electric brake 9 which may be of any ordinary or preferred form of construction, is mounted on the plate 6. The brake shown has a brake lever 10 which is pivoted at 11 and extends out beyond the edge of the turntable 7 where it is provided with a brake 12 which is adapted to engage with the outer edge of the table for stopping the same. This lever is provided with a handle 13 for swinging it to adjusted position. A spring 14 tends to draw the lever 10 so that the brake 12 will engage with the table. A spring catch 15 has a slot 16 for engagement with the pin 17 to which the spring 14 is attached. When the catch 15 is in the position shown in Figure 1 it will hold the lever 10 in adjusted position but when the catch is moved to the right the lever is released and will be drawn forward by the spring 14. A magnet 18 is arranged adjacent to the catch 15 and is adapted, when energized, to draw the catch forward to release the lever. One end of the magnet coil is connected to an insulated terminal 19 which is adapted to be engaged by a spring contact 20 on the lever 10 when the lever is in disengaged position. This forms a ground connection for one terminal of the magnet, but when the lever swings forward the contact is broken at this point. The other terminal is connected by wire or conductor 21 to a battery 22. The other terminal of this battery is connected by a conductor 23 with a contact or terminal 24 which forms one part of the electric switch which is associated with the sound box or reproducer 25. This reproducer is of the type used on the Edison talking machines and has a floating weight 26 which is pivotally mounted on a vertical pivot 27 so that its free end may swing laterally. This end is provided with the usual stop pin 28 which engages with a loop or keeper 29 to limit the movement of these parts with respect to each other.

At the rear end of the reproducer I mount a bracket or support 30 having a bottom plate 31 and side walls 32. The side walls are continued forwardly to form arms 33 which engage with the sides of the reproducer and these arms are connected by cross

braces 34 and 35 which engage with the end of the reproducer so as to firmly support the bracket 30. The bracket is held in position by means of a screw 36 which passes through 5 the plate or cross piece 35.

An arm 37 is secured to the hub or inner end 38 of the floating weight. This arm may be attached in any convenient manner as by means of a split yoke or clamp 39, the 10 parts of which are held against the hub by means of a bolt 40. A spring 41 is mounted in the bracket 30 and engages with the arm 37 and tends to press this arm in the direction which it will move when the floating 15 weight reaches the end of the groove and moves to the left as seen from the front or outer end of the reproducer. Any suitable spring may be utilized, as for instance a flat spring which is connected at 42 to the bracket 20 30 and which may be adjusted by means of an adjusting screw 43. The outer end of the arm 37 has a pin or projection 44 which engages with a slot 45 in one end of a lever 46 which is pivoted at 47 to the bottom of 25 the bracket 30. The lever 46 projects rearwardly or is provided with a resilient contact member 48 which is adapted to engage with the adjustable contact 24. This contact is insulated from the bracket 30 by 30 means of an insulating washer or collar 49. It will be noted that the pin 44 engages with the lever 46 at a point which is nearer the pivot 47 than is the outer end of the contact 48 so that the movement of the pin will be 35 considerably multiplied by the movement of the lever. The lever 46 is grounded through the frame of the machine so that a circuit is provided to the grounded side of the magnet 18.

40 When the reproducer 25 reaches the end of the groove in the record the swinging weight 26 moves to the left, which causes the arm 37 to swing to the right. This movement is accentuated or made more positive by the spring 41. This swings the lever 46 so as to bring the contact 48 into engagement with the terminal 34 and the circuit is closed from the battery 22 to the magnet 18. This will cause the magnet 45 to attract the catch or armature 15 and thereby release the brake lever 10 which engages with the table 7 and stops the rotation of the same. As the lever 10 swings forward, the circuit is broken by the contact 50 55 20 moving away from the contact 19, which prevents unnecessary loss of current. When the lever 10 is moved to its initial position and the reproducer is returned to operative position, the parts will be adjusted so that 60 it will be in position for the next operation, as above described.

From this description it will be seen that I provide a unique automatic stopping mechanism which may be readily applied to phono-

graphs of this type and which will be substantially certain of operation. 65

Having thus described my invention, which, however, I do not wish to limit to the exact arrangement of parts or details of construction herein shown and described, what 70 I claim and desire to secure by Letters Patent is:

1. An electric switch member for an Edison phonograph having a reproducer with a floating weight, comprising a support, an insulated contact member carried by said support, and a second contact member adapted to be connected with the floating weight and actuated thereby for making contact with the first named contact member. 75 80

2. A switch attachment for an Edison phonograph, comprising a support adapted to be secured to the reproducer, a contact member carried by said support, a second contact member adapted to be connected with and actuated by the floating weight to make contact at times with the first named contact member, one of said contact members being insulated and the other grounded. 90 95

3. The combination with an Edison reproducer and its floating weight, of a spring tending to move the floating weight out of normal position and in the direction which it moves when it reaches the end of the record groove. 95

4. The combination with a reproducer having a floating weight, of a spring tending to swing the floating weight laterally in one direction, and an electric switch adapted to be actuated by the movement of the floating weight. 100

5. In a device of the character set forth, the combination with a reproducer having a floating weight, of a bracket, an insulated terminal mounted in said bracket, an arm secured to the floating weight of the reproducer and a lever pivotally mounted in the bracket, said lever having a short end engaging with the arm and a long end forming a contact for engagement with said terminal. 105 110

6. The combination with an Edison phonograph reproducer, of a bracket secured to the rear end of the reproducer, an insulated terminal mounted in said bracket, an arm secured to the floating weight of the reproducer, a spring between the bracket and the arm tending to swing the weight in one direction and a contact lever mounted in the bracket and having one end engaged by said arm for swinging the lever and the other end adapted to make contact with said terminal. 115 120

7. The combination with a phonograph having the usual turntable and operative parts, of an electric stop mechanism, including an actuating magnet, means for 125

grounding one terminal of the magnet, a battery, a connection from the battery to the other terminal of the magnet, an insulated contact member carried by the reproducer 5 and a grounded contact member also carried by the reproducer, said contact members being out of engagement when the reproducer is in normal playing position and adapted to make contact when the reproducer reaches 10 the end of the groove in the record.

8. In a machine of the character described, the combination of a rotatable support, means for operating the same, an electric brake mechanism and a sound box com-

prising relatively movable coacting parts in 15 electric connection and a circuit closer actuated by said sound box to control the operation of the brake mechanism.

9. In a machine of the character described, the combination of a movable member, electrically controlled means for governing the movement thereof, a sound box comprising relatively movable coacting parts and a circuit closer adapted to be actuated by said parts for governing the opera- 20 25 tion of said electrically controlled means.

WILLIAM R. DUNCAN.
